[57] **CLAIM**

The ornamental design for a bottle, as described and shown.

DESCRIPTION

FIG. 1 is a perspective view of a first embodiment of a bottle embodying the new design;
 FIG. 2 is a front elevational view of the bottle of FIG. 1, the rear elevational view is the same;
 FIG. 3 is a side elevational view of the bottle of FIG. 2 (both sides being identical);
 FIG. 4 is a top plan view of the bottle of FIG. 2;
 FIG. 5 is a bottom plan view of the bottle of FIG. 2;
 FIG. 6 is a front elevational view of a second embodiment of the bottle embodying the new design; and,
 FIG. 7 is a front elevational view of a third embodiment of a bottle embodying the new design.
 The second and third embodiments are the same as the first embodiment except for the number of grooves on the sides of the bottle.
 The broken line showing of a bottle neck is for illustrative purposes only and does not form part of the claimed design.
